DESIGN FOR A FABRIC

Robert Solomon, New York, N. Y., assignor to Bernard Kavaler, New York, N. Y., doing business as Bernard Kavaler Co.

Application July 25, 1945, Serial No. 120,939

Term of patent 3½ years

(Cl. D92—1)

To all whom it may concern:

Be it known that I, Robert Solomon, a citizen of the United States of America and a resident of the city of New York, in the county of New York and State of New York, have invented a new, original, and ornamental Design for a Fabric, of which the following is a specification, reference being had to the accompanying drawing,
forming a part thereof.

The figure is a face view of a fabric showing my new design.

I claim:

The ornamental design for a fabric, substantially as shown.

ROBERT SOLOMON,
